UNITED STATES PATENT OFFICE.

FRANÇOIS LEONIDAS GUILMET, OF SAN FRANCISCO, CALIFORNIA.

AIR-BRAKE.

SPECIFICATION forming part of Letters Patent No. 722,837, dated March 17, 1903.

Application filed October 31, 1894. Serial No. 527,541. (No model.)

To all whom it may concern:

Be it known that I, FRANÇOIS LEONIDAS GUILMET, a citizen of France, residing in the city and county of San Francisco, State of California, have invented certain new and useful Improvements in Air-Brakes, of which the following is a specification.

My invention relates to quick-acting automatic air-brakes; and its principal objects are, 10 first, to provide a quick-acting triple valve in which the speed of what is known as "quick-acting" feature will be as great as can possibly be attained with the sole agency of air-pressure; second, to make such quick-acting 15 feature thoroughly reliable and efficient at all times, irrespective of conditions—that is, whether the brakes are already partly or fully applied or not and no matter what amount of dirt may be present in the train-pipe and its 20 connections; third, to effect an automatic discharge of such dirt and of water of condensation which collect in the train-pipe and the valve-chambers; fourth, to facilitate the release of the brakes after an emergency stop. 25 The invention comprises also a novel and improved arrangement of graduating-valve, permitting the same to remain firmly seated when the brakes are partly applied.

The principal advantages of my improved 30 triple valve are secured or rendered practicable by discharging a part of the train-pipe pressure, preferably into the atmosphere, and effecting the closure of the discharge-passage by a new method or principle, which will be 35 fully described hereinafter. With the brakes in common use the train-pipe pressure is expanded into the brake-cylinders for producing quick action in emergency stops. This 40 practice of admitting train-pipe pressure into the brake-cylinders in emergency is objectionable for many reasons. First, it is unnecessary and undesirable that the full braking power available in service stops should be any less than the full power available in emergency. What is the safe limit of braking 45 power for service stops is necessarily the same for emergency stops, or vice versa, and there should be no liability of ever being exceeded at any time. Second, the space available in 50 the brake-cylinder for relieving train-pipe pressure is a very variable quantity, not only

on account of variation in travel of the brake-piston, but also because when the brakes are partly applied the space is partly taken up and the action of the emergency-valves is very 55 uncertain and cannot be trusted, yet it is just when the brakes are partly applied that the efficiency of the emergency-valves is most frequently desirable or indispensable. Third, with train-pipe pressure admitted to the brake-cylinder in emergency the auxiliary-reservoir pressure is but slightly reduced, and a quick 60 release is thereby rendered doubtful, principally on long trains. Fourth, dirt accumulating in the train-pipe cannot be discharged 65 into the brake-cylinder for obvious reasons. Fifth, the quick-action feature must be most rapid when pressure from the train-pipe is vented into the open air.

In this specification and the appended 70 claims whenever I use the term "graduating-valve" I mean a valve which controls the admission of pressure from the auxiliary reservoir to the brake-cylinder in service stops, and "graduating-spring" the spring or other 75 appliance which arrests the triple-valve piston at the proper point for service stops. By the term "emergency-valve device" I mean the part or parts which are designed for producing 80 what is known as "quick action," whether dependent or independent from the plain triple valve. The terms "emergency-piston" and "emergency-valve" will of course designate component parts of such device. All such 85 terms are well understood by those skilled in the art to which the invention pertains. When using the term "equilibrium of fluid-pressure," I intend to include atmospheric pressure; but the term "fluid-pressure" or "fluid under pressure" when used without the word 90 "equilibrium" in conjunction will be meant for a higher than atmospheric pressure. In using the term "discharge-passage from the train-pipe" I mean a passage through which pressure is relieved from said pipe without 95 reference to where the pressure thus relieved may go; but by the term "exhaust-passage from the train-pipe" I mean a passage leading from the train-pipe to the atmosphere, whether all the pressure in the train-pipe or 100 only a part thereof is exhausted through said passage. By the term "valve device" I

mean any valve or set of valves connected or unconnected, but adapted to co-operatively effect a given result or results.

In the accompanying drawings, Figure 1 is a vertical section through one form of triple valve embodying my invention. Fig. 2 is a section on the line $x-x$ of Fig. 1. Fig. 3 is a horizontal section through the bushing 12, showing the seat of the slide-valve 5. Fig. 4 shows the face of the slide-valve 5. Fig. 5 is a section on the line $z-z$ of Fig. 4. Fig. 6 is a vertical section through a modified construction, and Fig. 7 shows a second modification of a detail in Fig. 6.

15 1 2 3 are parts of the valve-casing.

4 is the triple-valve piston; 5, the slide-valve of the triple valve; 6, the graduating-valve; 7, graduating-spring abutting against a stationary piston 8, which is made air-tight 20 by means of the rubber gasket 9 and metallic gasket 10 and fits in the tube formed in the piston 4; 11, sleeve fast in part 1 of the valve-case, at the end of which the seat of valve 6 is formed and acting also as a guide for 25 the piston 4; 12, bushing into which the flat seat of valve 5 is formed; 13, spring holding valve 5 to its seat; 4^a, sleeve fastened to or made integral with piston 4; 14, strainer; 15 16, parts of inner casing or shell for the 30 emergency-valve device; 17, emergency-piston; 17^a, piston-rod; 18, emergency-valve; 19, emergency-valve spring; 20 21, packing-rings for rod 17^a; 22, rubber or leather gasket in valve 18; A, train-pipe connection; 35 B, auxiliary-reservoir connection; C, brake-cylinder connection; D, feed-port, preferably tapering, as shown, and may also be a groove; E, passage from feed-port to auxiliary reservoir; F, service-stop port or passage; G, emergency-port normally in communication with the exhaust-port H through cavity I in valve 5; J, passage to emergency-piston chamber; K, chamber of slide-valve 5; L, chamber of piston 4; M, chamber of piston 17; M', space 45 of predetermined volume; N, port of predetermined size through which pressure is admitted to or exhausted from one side of piston 17; O, discharge port or passage from the train-pipe; P P, ports between chamber K 50 and the auxiliary reservoir; Q, emergency-valve chamber; R, small leak at the edge of port J; S S, bolt-holes in flange T.

The sleeve 4^a is provided near the end with a series of inner lugs or notches U, adapted 55 to catch valve 6, and a series of grooves V, parallel to the lugs, one lug and a groove only being shown.

From the main train-pipe the air-pressure reaches into the auxiliary reservoir through 60 passage A, chamber L, port D, and passage E. Thence it flows into chamber K through passages P P, and from chamber K into chamber M through port J.

The piston 4 has the usual slight range of 65 independent motion before catching valve 5 in moving either way. In service stops the piston 4 moves alone first to the left, covering

port D. Then it moves together with valve 5 until the lugs U catch valve 6, and the exhaust-port H is then out of communication 70 with port G. A little further motion of the piston to the left will unseat valve 6 against the resistance of spring 7, and auxiliary-reservoir pressure will be admitted to the brake-cylinder through grooves V and passages F 75 and C, and on equalization of auxiliary-reservoir pressure with that in the train-pipe the spring 7 will close valve 6 and hold it firmly seated if the air-pressure has any tendency to leak around it. It will be seen that although the valve 6, spring 7, and piston 8 are held in the piston 4 they remain undisturbed until the latter piston unseats valve 6, and piston 8 is never disturbed. If a sudden fall of pressure occur at any point in the train-pipe, the piston 4 will make a full stroke to the left, and the parts J H will then be brought 80 into communication with each other through cavity I in valve 5, thereby quickly relieving the pressure on top of piston 17. The pressure in the space M' will also be relieved, but having to pass first through the restricted port N will not escape so quickly and will have time to momentarily lift piston 17 and valve 18, thereby venting train-pipe pressure 85 into the atmosphere or elsewhere; but as soon as the pressure in the space M' is exhausted the spring 19 will close valve 18. It will be understood that by properly proportioning the size of ports N O and that of 90 space M with the volume of air contained in a car-section of train-pipes any desired amount of pressure may be relieved from the train-pipe. The communication between ports J H will be partly established before the port G 95 is uncovered and will be still maintained after full opening of port G, through which the auxiliary-reservoir pressure will quickly equalize into the brake-cylinder. With the valve 5 at the service-stop position the port 100 J is partly or fully covered by it; but in order to prevent the pressure in chamber M and space M' being fully exhausted by leakage communication of that chamber with chamber K is maintained through a minute 105 groove R at the edge of port J, so that if an emergency stop is desired when the brakes are partly applied there will be pressure in the space M' for operating the emergency-valve. It is quite unnecessary that the emergency or quick-action feature should be able 110 to take place two or more times in succession, yet such feature could be readily obtained simply by adjusting the emergency-valve device in such way as to effect a reduction of 115 pressure in the train-pipe only about equal to the reduction occurring in the auxiliary reservoir by expansion into the brake-cylinder. This would permit the spring 7 to retract the piston 4 immediately after equalization of 120 auxiliary-reservoir pressure into the brake-cylinder, and the space M' would then be re-filled with pressure and ready for another 125 quick action; but I deem it preferable to effect 130

a reduction of pressure in the train-pipe of about five pounds in excess of the reduction occurring in the auxiliary reservoir, or, say, about twenty-five pounds reduction in the 5 train-pipe and twenty in the auxiliary reservoir.

It is desirable that the flanges T T' should be of such size or form as to retain interchangeability of connection with the applications in actual use; but it is still more desirable to secure perfect drainage of chamber L, as any moisture freezing in that chamber may interfere with the operation of the brakes. In order to harmonize these two desirable conditions, the center of flanges T T' is on a 15 lower plane than the center line of the chambers K L, and in this way the passage E may lead from the bottom of chamber L to the auxiliary reservoir in a horizontal plane, thereby 20 effecting perfect drainage of chamber L and permitting also any dirt passing through the strainer 14 to find its way into the auxiliary reservoir instead of having a tendency to remain in chamber L. The flange T should be 25 preferably fastened on one side of the auxiliary reservoir or of the brake-cylinder in a way such as to direct the pressure from the train-pipe into chamber Q in a straight line, as every angle in the pipes retards the motion of the 30 fluid, so, also, do the strainers when located in the usual manner, even if kept perfectly clean, which is seldom the case, for the dirt accumulates in a pretty short time and obstructs the strainers in part at least, thereby 35 regarding the quick-action feature when not stopping it entirely; but with my device no strainers are required between the main train-pipe and the chamber Q. Whenever the quick-action feature of the brake is brought 40 into play, a solid stream of fluid will shoot out in a nearly-straight line without meeting with any obstacle and carrying with it any dirt or water in the vicinity of valve 18, and the most troublesome element to be contend- 45 ed with in the use of air-brakes will thus be removed. The strainer 14, which is placed in the branch of passage A leading to chamber L, having a large space beneath it and its outer face being turned in direction of 50 passage A, through which the dirt is supplied, it can never become filled and packed solid with dirt, as is frequently the case with the brakes in use. It is also located so as to be easily inspected without breaking the train- 55 pipe joint at A by simply removing the part or cap 2.

The outer diameter of the inner shell 15 is somewhat larger at the bottom than at the top, so as to facilitate removal for inspection. 60 It will be observed that the face and seat of valve 18 are unlike the common arrangement of disk valves, whose face or seat carry a gasket of soft material. My arrangement, which is susceptible of modifications of de- 65 tail, will be understood from the drawings and has for its object to prevent any grit or dirt to remain on or around the valve-face or

its seat when pressure is discharged from the train-pipe; but while I have illustrated what I deem one of the best arrangements of valve 70 for the purpose of cleaning the train-pipe and claim its new features I do not wish to limit myself to any particular detail or form of construction of the valve device controlling the removal of dirt from the train-pipe, but to 75 one that has no considerable tendency to become quickly deranged or leaky by the presence of dirt on, around, or near it, and is adapted to free itself from such dirt, so that strainers may be dispensed with between the 80 main train-pipe and the discharge-passage, if desired. The valve-seat and the valve-face are inclined, so that the direction in which the dirt would naturally tend to fall is the same as the direction in which it would be 85 carried by the flow of air through the passage, and when the valve is unseated any dirt which may be caught on the face of the valve will drop off or be blown off into the passage.

In the modification illustrated by Fig. 6 90 the space or chamber M' is normally filled with pressure, as in the former design, but is normally out of communication with the emergency-piston 17, and the piston-chamber M is normally exposed to atmospheric pressure, 95 but is brought into communication with the space M' when the piston 4 makes a full stroke to the left. The exhaust-port H is adapted to communicate at times with the brake-cylinder and permanently with the 100 chamber M. When the piston 4 makes a full stroke to the left, the passage J communicates with the port and passage J^A through the recess I in valve 5, and the pressure in the space or chamber M' is suddenly brought 105 beneath the piston 17, from where it escapes more slowly through port N and the large exhaust-passage H.

The port O may open into an expansion-chamber 3' of determined size, so as to gage 110 the amount of air to be drawn from the train-pipe. In this event the port O could remain open for a longer space of time than if the expansion-chamber is absent, and when closed the pressure remaining in the chamber 115 3' would be vented through the small port W. It is obvious that the closure of the passage O will be effected by valve 18, whatever the destination of the pressure relieved from the train-pipe may be; but if admitted into the 120 brake-cylinder a check-valve should be located in passage O for preventing backflow from the brake-cylinder to the train-pipe.

The casing 15 makes with the bushing 15' a tapering joint, which is thus rendered tight. 125 The joint may also be formed directly with the outer casing, and the bushing is considered as an integral part of the outer casing.

The piston 17 may be actuated by pressure either from the train-pipe, from the auxiliary reservoir, or from any other limited or unlimited source of supply—such, for instance, as is shown in the modification of detail Fig. 7, in which said piston is actuated by aux-

iliary-reservoir pressure when the valve 5 advances to the left until the recess or groove J^B communicates with the port J through the recess I. In this case the pressure is gradually admitted into the space M' through port N instead of being gradually discharged from said space, as before described. The air in the chamber M below the piston is exhausted through the passage J, I, and H.

10 It will be understood that while I utilize a piston and a slide-valve of a triple valve for controlling the pressure on the emergency-valve device such control could be effected by a valve designed for the purpose, whether 15 performing other functions or not. It will be evident also that the piston 17 can be fitted loosely in its chamber, so as to permit leakage of pressure around it, and the port N dispensed with. I consider such leakage as the 20 equivalent of the port N.

What I claim as new, and desire to secure by Letters Patent, is—

1. In an automatic fluid-pressure brake system, the combination, with a train-pipe, an auxiliary reservoir, and a brake-cylinder, of an emergency-valve controlling the release of fluid from the train-pipe, a piston by whose movement the emergency-valve is operated and which is located in a chamber which is disconnected from the train-pipe and from the brake-cylinder in the application of the brakes, a triple - valve device controlling ports by which fluid is admitted to and released from the chamber, and a passage 35 through which the pressures on opposite sides of the piston may be equalized when the brakes are applied, substantially as set forth.
2. In an automatic fluid-pressure brake system, the combination, with a train-pipe, an auxiliary reservoir and a brake-cylinder, of an exhaust-passage through which fluid is released from the train-pipe to the atmosphere, an emergency - valve, a movable abutment which is actuated by fluid-pressure to open 45 the exhaust-passage, a triple-valve device, a passage controlled by the triple-valve device for admitting fluid under pressure to the

brake-cylinder, a passage controlled by the triple valve through which fluid under pressure is supplied to the movable abutment, 50 and a normally open port or passage through which fluid-pressures on opposite sides of the movable abutment may be equalized and thereby permit the closure of the exhaust-passage, substantially as set forth.

3. In a triple valve, the combination of a piston, a main valve operated thereby for controlling the exhaust from the brake-cylinder and the supply from the auxiliary reservoir to the brake-cylinder in emergency applications, a graduating-valve also operated by the piston, a stationary seat therefor and a spring having a support independent of the piston for holding the graduating-valve to its seat.

4. In a triple valve, the combination of a piston, a main slide-valve having a lost-motion connection with the piston and controlling the exhaust from the brake-cylinder, and the supply from the auxiliary reservoir to the brake-cylinder in emergency applications, a graduating-valve operated by the piston, a stationary seat therefor and a spring having a support independent of the piston for holding the graduating-valve to its seat.

5. In an air-brake, the combination, of a triple-valve casing, a piston-chamber formed in said casing, an auxiliary reservoir, and a port or passage leading from the bottom of the piston - chamber to the auxiliary reservoir, 80 said passage being entirely below the bottom of the piston-chamber whereby the said chamber will drain into the auxiliary reservoir.

6. In a triple-valve device, a piston-chamber, a cap closing the end of the piston-chamber, a passage in the main casing leading from the train-pipe, a passage in the cap leading to the piston-chamber and a removable strainer located at the juncture of these passages.
